INVENTOR

Richard H. Stevens.

BY

R. S. C. Dougherty
ATTORNEY

UNITED STATES PATENT OFFICE.

RICHARD H. STEVENS, OF JOHNSTOWN, PENNSYLVANIA, ASSIGNOR TO BETHLEHEM STEEL COMPANY.

WATER-COOLED FURNACE ROLLER.

Application filed January 26, 1927. Serial No. 163,617.

My invention relates to that class of devices for cooling rotating members used in furnaces, or other heated environment. More particularly, it is directed to means for cooling rolls used in furnaces, such as charging rolls in metal treating furnaces.

It is common to provide for the cooling of such rolls by making them hollow and passing water therethrough. A defect of such schemes is due to the fact that steam and other gases are liberated and trapped in the upper part of the roll. While there may be a continuous circulation of the water, the gases remain in the roll, frequently occupying a substantial space, with the result that unless the roll is constantly rotated the metal thereof is burned, which obviously is a serious disadvantage.

The purpose of my invention is to provide means for effecting the constant escape of steam and gases in water-cooled rolls.

My invention consists essentially of a device for entrapping steam and gases liberated in water-cooled rolls and for removing such gases by the rotation of the roll.

Referring to the accompanying drawings for a specific embodiment of this invention:

Fig. 1 is a vertical longitudinal section of the roll and the gas and water separation device, the roll being shown in position for end charging a furnace;

Fig. 2 is a plan view of a charging roll together with the attached device for removing the water and gases;

Fig. 3 is a transverse vertical section through line III—III of Fig. 1; and

Figs. 4 and 5 are transverse vertical sections, on a larger scale, through the water and gas separating device, taken through the two annular channels of this device.

In the end of furnace 1 is mounted the hollow charging roll 2, rotatably carried in cylindrical bearings 3 and turned by means of gear 4 fixed thereto and meshing with gear 4' on shaft 5, operated from a suitable source of power through the intermediary of bevel gearing 6 and shaft 7.

Bolted to the open end of roll 2 is the chambered casing 8, covering which is casing 9, open at the bottom 10. Centrally of casing 8 and axially of the roll 2 is lug 11 having a passage 12 axially thereof. This passage is continuous with passageway 13 of tube 14 which is mounted at one end in the shoul- dered recess 15 of lug 11, and at the other end,

in the recessed lug 16 axially disposed at the other end of the roll. This tube opens into chamber 17 of the roll through openings 18 of lug 16.

The cylindrical bearing 3 is cooled by means of water fed thereto through pipe 19 which enters and passes through the annular chamber 20, then out through pipe 22, flowing thence through stuffing box 23 through the passageway 12 of lug 15, and then through tube 14 into chamber 17 to cool the same.

Between lug 11 and the inner wall 24 of member 8 are chambers 25 and 26 communicating with chamber 17 of the roll, and separated from each other by partitions 27. These chambers communicate with annular channels 28 and 29 by means of ducts 30 and 31 respectively, the ducts communicating with one annular channel being to one side of lug 11 while the ducts communicating with the second annular channel are on the opposite side of this lug.

Channel 28 discharges to the outside of member 8 at 32 while channel 29 opens at 33, these two openings being on opposite sides of member 8.

As indicated in the drawings, both ends of any particular channel are on the same side of the casing. It should be noted that the chambers which discharge into a particular channel do so at the inner end portions of the channel. For example, opening 32 is on the same side as the duct entering the inner end of channel 28 both ducts 30 entering the portions of channel 28, nearest the inner end.

Beneath casing 8 is drain trough 34.

The operation of the device is more or less obvious. Roll 2 is cooled by water entering chamber 17 from pipe or tube 14, which then passes through chamber 17 to chambers 25 and 26 and thence through ducts 30 and 31, channels 28 and 29 and out through openings 32 and 33 into the drain trough.

Obviously the steam and gases rise to the top of the roll and pass therefrom into chambers 25 and 26 as, by rotation of the roll, one after the other comes into the topmost position, passing through the ducts into the channels. As the gases and steam are always at the top of the casing it is obvious that the rotation indicated by the arrows in Figs. 4 and 5 will cause the entrapped gases to occupy progressively different positions of the channels until the exit openings of the channels reach the uppermost position when they will escape.

into casing 9, and thence to the atmosphere.

While I have shown my invention in but one form, it will be obvious to those skilled in the art that it is not so limited, but is susceptible

5 of various other changes and modifications without departing from the spirit thereof, and I desire, therefore, that only such limitations shall be placed thereupon as are imposed by the prior art or as are specifically set forth 10 in the appended claims.

Having described my invention what I desire to claim is as follows:

1. In combination with a water-cooled roll, 15 means for receiving and entrapping steam and gases liberated from the water and means effective upon the rotation of the roll to permit the escape thereof.

2. A device for removing steam and gases from a water-cooled roll, comprising a casing 20 attached thereto, spaces within such casing effective upon rotation of the roll to collect and entrap the steam and gases, and a passageway within such device effective upon rotation of the roll to permit their escape.

25 3. In combination with a water-cooled roll, chambers communicating with the interior of the roll, a passageway open to the outside communicating with the chambers, whereby rotation of the roll entraps the steam and 30 gases in the passageway and further rotation permits them to escape.

4. In combination with a water-cooled roll, 35 a device attached to the open end of the roll, chambers in such device disposed about the axes of the roll and communicating with the interior thereof, an annular channel communicating with the chambers, this channel

opening at one end to the outside, whereby rotation of the roll entraps the steam and gas in the channel and further rotation liberates 40 them through the outside opening.

5. In combination with a water-cooled roll, a casing fixed to the end of the roll having chambers disposed about the axis of the roll and communicating with the interior thereof, 45 adapted to receive gases and steam therefrom, an annular channel in said casing disposed outside of said chambers and communicating therewith, said channel also having an opening to the outside, whereby rotation of the 50 roll first entraps the steam and gases in said channel and then liberates them through the outside opening.

6. In combination with a water-cooled roll, 55 means rotatable with the roll, having chambers communicating with the interior of the roll, a plurality of channels in said means having discharge openings angularly disposed relative to each other, the inner ends of the channels being angularly disposed relative to each other and communicating with the chambers.

7. A device for removing steam and gases from a water cooled roll, comprising a casing 65 attached thereto, spaces within such casing effective upon rotation of the roll to collect and entrap the steam and gases, and a passageway within such device having an exit portion adapted to be brought into an upwardly extending direction upon rotation of 70 the roll, to permit their escape.

In testimony whereof I hereunto affix my signature.

RICHARD H. STEVENS.
